UNITED STATES PATENT OFFICE

SIGURD CLAUSEN, OF BROOKLYN, NEW YORK, ASSIGNOR TO INTERNATIONAL CIGAR MACHINERY COMPANY, A CORPORATION OF NEW JERSEY

CIGAR MACHINE FEEDING CHANNEL

Application filed August 21, 1931. Serial No. 558,552.

This invention relates to improvements in cigar machines, and more particularly to the tobacco feeding channel of the same, its main object being to provide means for preventing the tobacco leaves on the conveyor from turning back and doubling over when entering the filler forming mechanism. With this and other objects not specifically mentioned in view, the invention consists in certain constructions and combinations hereinafter fully described and then specifically set forth in the claims hereunto appended.

In the usual constructions of tobacco feeding channels in cigar machines the tobacco leaves for the filler of a cigar bunch are placed by an operator into a feeding channel composed of a moving endless horizontal belt and two moving endless vertical belts, the channel so formed carrying the inserted tobacco layer to the filler forming mechanism which comprises compacting, cutting and measuring devices adapted to form fillers of uniform size and density. When the advancing tobacco layer in the feed channel enters under the compacting device, which is stationary in relation to the moving tobacco mass, any upstanding leaves in the layer tend to be caught by the forward edge of the compactor and turned back upon the layer, thus forming hard spots in the same which will impair the homogeneity of the finished cigar bunch.

The means employed in the present invention to prevent this occurrence comprises stationary ledges projecting into the tobacco channel along both sides of the channel which are formed by the vertical side belts, thereby holding down the edges of the leaves and preventing them from curling up, these ledges leading the leaves under a travelling inclined belt dipping into the channel immediately in front of the compactor, the said inclined belt running faster than the feed belts and in the same direction as the latter, thereby laying down in the forward direction any upstanding tobacco leaves and leading them head-on into the compactor. The inclined belt is provided with lead-in plates for guiding any leaves which may overhang the ledges under the belt, and with a stripper for pre-

venting the straightened leaves from being lifted out of the channel by the belt.

When broad filler leaves reaching across the entire width of the feed channel are used, the retaining ledges are sufficient to keep the leaves flat in the channel; and then the inclined belt may preferably be omitted.

In the accompanying drawing which forms a part of this specification and in which like characters of reference indicate the same or like parts:

Fig. 1 is a side elevation of the improved cigarette machine tobacco feeding channel;

Fig. 2 is a sectional end elevation, taken on line 2—2 of Fig. 1;

Fig. 3 is a top view of the feeding channel, seen from line 3—3 of Fig. 1; and

Fig. 4 is a top view from line 4—4 of Fig. 1.

In carrying the invention into effect there is provided a plurality of travelling feed belts arranged to form a tobacco feeding channel, stationary ledges projecting into said channel along the sides thereof for holding down the edges of tobacco leaves in the channel, a compactor adapted to compress the tobacco in the channel, an inclined travelling belt adapted to lay down any tobacco leaves upstanding from the tobacco between the ledges and the compactor, plates overlying said ledges and adapted to guide the tobacco leaves which may overhang said ledges under the inclined belt, and a stripper having one end engaging said inclined belt. In the best forms of construction contemplated, the free end of the stripper and the forward end of the compactor are forked and the prongs of the compactor extend between the prongs of the stripper to cause the top leaves of the tobacco in the channel to be properly guided under the compactor. In the preferred form of construction the ledges are supported from castings which are carried by a table underlying the channel and which serve to support the sides of the channel. The inclined belt preferably runs faster than the feed belts and in the same direction to lay down any tobacco leaves upstanding from the tobacco in the channel. The various means and parts may be widely varied in construction within

the scope of the claims for the particular device selected to illustrate the invention is but one of many possible concrete embodiments of the same. The invention, therefore, is not to be restricted to the specific construction shown and described.

Referring to Figs. 1, 2 and 3, the improved tobacco feeding channel consists of an endless horizontal belt 10 driven at a suitable speed over a support table 11 onto which it is guided by a pulley 12 mounted on a shaft 13, and of two endless vertical belts 14 running at the same speed over flanged pulleys 15 which run in opposite directions and guide their inside loops onto the horizontal belt 10. The pulleys 15 turn on shafts 16 supported by a bracket 17 attached to the frame of the tobacco feed. The inside loops of the belts 14, which form the moving side walls of the tobacco feed channel, are supported by castings 18 which fit into the spaces between the loops of each of the belts 14 and are fastened to table 11.

To the top of each of the castings 18 is fastened, by means of screws 19, a guard 20 which projects over and along the outer loop of belt 14. To prevent the edges of the tobacco leaves T from turning up in the feed channel, the guards 20 are extended inwardly and downwardly to form ledges 21 projecting into the tobacco channel near each wall and presenting flat horizontal surfaces which hold down the opposite edges of any broad tobacco leaves which may be inserted into the feed channel.

The edges and points of any narrow leaves which may not be held down by the ledges 21 are guided by lead-in plates 22, which are adjustably attached to the guides 20 by screws 23, against an inclined endless belt 24 running over pulleys 25 and 26, on shaft 27 and stud 28 respectively, and driven at high speed by a belt 29 running over pulley 30 on shaft 27. Stud 28 is stationarily supported by a plate 31 attached at its upper end to frame 32 of the machine, while shaft 27 is adjustably mounted in arms 33 pivoted on stud 28 and held at the proper angle by a bolt 34 adjustably carried by a link 35 pivoted on a stud 36 in plate 31. The arms 33 have adjusting screw 37 bearing against the journal boxes 38 of shaft 27 which can thereby be adjusted for the proper tension of belt 24. The shaft 27 is supported intermediate the pulleys 27 and 30 by a bracket 39 adjustably attached to frame 32 by means of a bolt 40.

To a stud 41 in plate 31 is clamped a stripper 42 bearing against belt 24 to prevent tobacco from being lifted out of the channel by the belt. The forward end of this stripper is cut into individual prongs between and outside of which pass the prongs 43 of the compactor 44 so that the top leaves of the tobacco layer T in the feeding channel are guided head-on under the compactor, from

which the compacted tobacco layer is carried to devices, not shown, for measuring and cutting the tobacco into filler for the cigar bunches which are formed in the cigar machine.

What is claimed is:

1. The combination with a plurality of travelling belts arranged to form a tobacco feeding channel, of stationary ledges projecting into said channel along the sides thereof for holding down the edges of tobacco leaves in said channel, a compactor adapted to compress the tobacco in said channel, an inclined travelling belt adapted to lay down any tobacco leaves upstanding from the tobacco between said ledges and compactor, plates overlying said ledges and adapted to guide the tobacco leaves which may overhang said ledges under said inclined belt, and a stripper having one end engaging said inclined belt. 70

2. The combination with a plurality of travelling belts arranged to form a tobacco feeding channel, of stationary ledges projecting into said channel along the sides thereof for holding down the edges of tobacco leaves in said channel, a compactor adapted to compress the tobacco in said channel, an inclined travelling belt adapted to lay down any tobacco leaves upstanding from the tobacco between said ledges and compactor, plates overlying said ledges and adapted to guide the tobacco leaves which may overhang said ledges under said inclined belt, and a stripper having one end engaging said inclined belt. 80

3. The combination with a plurality of travelling belts arranged to form a tobacco feeding channel, of stationary ledges projecting into said channel along the sides thereof for holding down the edges of tobacco leaves in said channel, a compactor adapted to compress the tobacco in said channel, an inclined travelling belt adapted to lay down any tobacco leaves upstanding from the tobacco between said ledges and compactor, and plates overlying said ledges and adapted to guide the tobacco leaves which may overhang said ledges under said inclined belt. 95

4. The combination with a plurality of traveling feed belts arranged to form a tobacco feeding channel, of an inclined endless belt running faster than said feed belts and in the same direction arranged to lay down the tobacco leaves upstanding from the tobacco in said channel, and means for supporting and driving said belt. 125

5. The combination with a plurality of belts arranged to form a tobacco feeding chan-

nel, of stationary ledges projecting into said channel along the sides thereof for holding down the edges of tobacco leaves in said channel, each of said stationary ledges having an inwardly and downwardly beveled surface on its upper side to facilitate placing the leaves in said channel and under said ledges.

In testimony whereof, I have signed my name to this specification.
